[57] CLAIM

The ornamental design for a corner for tub surrounds or
the like, substantially as shown and described.

DESCRIPTION

FIG. 1 is a perspective view of a corner for tub surrounds or the like embodying our new design;
FIG. 2 is a front elevational view thereof;
FIG. 3 is a top plan view thereof;
FIG. 4 is a left side elevational view thereof;
FIG. 5 is a right side elevational view thereof;
FIG. 6 is a bottom plan view thereof; and
FIG. 7 is a rear elevational view thereof.

FIG. 1

FIG. 3

FIG. 2

FIG.4

FIG.7

FIG.5

FIG.6
